Primary Examiner — Cynthia Underwood*(74) Attorney, Agent, or Firm* — Buckingham, Doolittle & Burroughs, LLP(57) **CLAIM**

I claim the ornamental design for a PV nut, as shown and described.

DESCRIPTION

FIG. 1 is a perspective view of the PV nut;

FIG. 2 is a top view thereof;

FIG. 3 is a bottom view thereof;

FIG. 4 is a side elevation view thereof;

FIG. 5 is a side elevation view thereof; and,

FIG. 6 is a cross sectional view thereof, taken along line 6-6 in FIG. 2.

The broken lines are included for illustrative purposes only and form no part of the claim.
